UNITED STATES PATENT OFFICE

HERMAN C. KLINE, OF SPRINGFIELD, MASSACHUSETTS

DUST COLLECTOR

Application filed July 29, 1927. Serial No. 209,335.

This invention relates to a dust collector, the general object of the invention being to provide a casing having an inlet at its lower end and its upper end connected with the exhaust of a fan, with means within the casing for separating the dust from the air passing through the same.

Another object of the invention is to provide means for spraying water or other liquid in the casing, with a tank at the lower end of the casing for receiving this liquid and the dirt collected thereby.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a sectional view through one form of the invention.

Figure 2 is a plan view thereof.

Figure 3 is a section on line 3—3 of Figure 1.

Figure 4 is an enlarged sectional view through another form of the invention.

Figure 5 is a section on line 5—5 of Figure 4.

In these drawings, A indicates a casing which is formed of a central portion 1 and two end portions 2 and 3, the portions being fastened together by bolts or the like passing through flanges 4 at the ends of the portions or sections. The lower section 2 is provided with an inlet 5 and the upper end of the upper section is connected by a pipe 6 with the inlet of a fan 7, the shaft of which is shown at 8 and the exhaust at 9 so that air will be drawn through the inlet 5 through the casing into the fan. Trays 10 are placed in the central section, these trays being composed of bars spaced apart and each tray supports a body 12 of coke or other porous material. Spray pipes 13 are arranged in the central section above the body of coke and these pipes are adapted to be connected with a suitable

source of water or other liquid so that the coke will be sprayed and thus the air passing through the coke will be freed from the dust therein. One of the spray pipes 13 is arranged below the bottom tray for spraying the air as it enters the casing. Above each tray the casing is provided with a chute 14 by which the coke can be placed on the tray and the chutes are provided with downwardly inclined walls so that the coke will gravitate to the trays. A tank 15 is arranged under the casing and this tank is adapted to contain water or other liquid and the casing is provided with a tapered bottom 15' and a discharge tube 16 which extends into the water in the tank 15, so that the water from the spray pipes will pass into the casing 15 and carry with it the dirt collected from the air passing through the casing. The tank is provided with a discharge 17.

Figures 1, 2 and 3 show the casing formed of wood and of rectangular shape in cross section, while Figures 4 and 5 show the casing A' formed of metal and of circular shape in cross section.

From the foregoing it will be seen that the fan will create a suction in the casing so that air will be drawn through the inlet, and this air will pass through the casing and through the coke supported on the trays 80 thereof and will pass into the fan casing and be discharged therefrom free of dust, and the water sprayed on the coke will take all dust from the air as it passes from the casing.

This invention will not only act to separate dust from air, but will also free the air from acid fumes, such as are known to exist in dust in asphalt plants.

The improved dust collector will collect dust which is lighter than the air. The collector can be built very economically and is strong and simple in construction. There are no moving parts and, therefore, no parts to wear out and they require no attention. As no dust passes through the exhaust fan, fire and explosion hazards are reduced and the collector works with safety in factories and mills. It requires very little space and its use makes better working conditions for the working men.

The exhaust fan may, if desired, discharge the free-from-dust air back to the room from where it is taken, thereby eliminating or drawing out the warm air from the room in cool weather and bringing better working conditions for working men in warm weather.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A dust collector comprising a vertically disposed casing including a central section and end sections secured together, said end sections having tapered portions, an air outlet pipe connected to the tapered portion of the upper end section, a fan in the outlet pipe, an air inlet means laterally connected with the tapered portion of the lower end section, a tank below the tapered portion of the lower end section and aligned with the casing, said tank being in communication with the last mentioned tapered portion, superposed filtering material receiving trays in the casing, sprinkling means above the material on said trays and below the lowermost tray respectively whereby the air is moistened before and after passing through the material, and discharge means for said tank.

In testimony whereof I affix my signature.
